FLEXIBLE COUPLING FOR SHAFTS OR THE LIKE

Lawrence G. Seigel and Stephen Stasenko, Erie, Pa., assignors to Lovell Manufacturing Company, Erie, Pa., a corporation of Pennsylvania

Filed Mar. 24, 1961, Ser. No. 64,470

Term of patent 14 years

(Cl. D55—1)

FIG. 1

FIG. 2

FIG. 3

FIG. 4

FIG. 1 is a perspective view of a flexible coupling for shafts or the like embodying our new design;

FIG. 2 is a side view of the coupling shown in FIG. 1;

FIG. 3 is a side view of the coupling rotated ninety degrees from the position shown in FIG. 2; and

FIG. 4 is an end view of the opposite end of the coupling shown in FIG. 1.

We claim:

The ornamental design for a flexible coupling for shafts or the like, as shown.
